UNITED STATES PATENT OFFICE.

HENRY BURGESS, OF CHICAGO, ILLINOIS.

LOUNGE.

SPECIFICATION forming part of Letters Patent No. 359,009, dated March 8, 1887.

Application filed April 21, 1886. Serial No. 199,663. (No model.)

To all whom it may concern:

Be it known that I, HENRY BURGESS, of Chicago, in the county of Cook and State of Illinois, have invented a new and Improved 5 Lounge, of which the following is a full, clear, and exact description.

The object of my invention is to provide a new and improved lounge, which can be used as a receptacle for storing dresses and other 10 articles, and which can be taken apart for convenient transportation and storage.

The invention consists of a lounge jointed together in such a manner as to form a box, and having a hinged seat, which is the cover 15 of the said box.

The invention also consists of various parts and details and combinations of the same, as will be fully described hereinafter, and pointed out in the claims.

Reference is to be had to the accompanying 20 drawings, forming a part of this specification, in which similar letters of reference indicate corresponding parts in all the figures.

Figure 1 is a front elevation of my improvement, partly in section. Fig. 2 is a plan view 25 of the box part of my improvement. Fig. 3 is a vertical cross-section of the same on the line $x x$, Fig. 1; and Fig. 4 is a detail perspective view of the fastener.

The lounge A forms a box, B, provided with the rear part, C, which connects at its upper end with the head part D, and at the other end with the foot cross-piece E, and with the front part, F, which is attached to the 35 head-piece D and to the foot cross-piece E. The bottom of the box B is supported by the plates I, I, secured to the bottom edges of the rear part, C, and the front part, F, at each end. The head part D and the foot cross-piece E are each provided on their upper edges with 40 a hinge-plate, J, into which fits a hinge-plate, K, secured to the under side, at each end of the seat or cover H, which swings on the said hinge-plates J and K. A recess, L, is formed 45 in the said head-piece D and the foot cross-piece E, so as to permit the seat H to swing up, as shown in dotted lines in Fig. 3. To each inner end of the said parts C, D, E, and F is secured one, two, or more plates, M, having 50 downwardly-projecting guide-strips N,

and provided with a pawl, O, pivoted on the said plate M. A guide-plate, P, is also secured near the bottom of each of the above-named four parts C, D, E, and F. An angle-iron, Q, having on each arm a notch, Q', is fitted to 55 slide between two corresponding plates M, on parts joined together, and the angle-iron Q is held in place by the pawl O, engaging the notches Q'.

It will be seen that the box or trunk B can 60 be opened or closed by the hinged seat H, and dresses and other articles can be stored in the said box.

The lounge can be taken apart by disengaging the pawls O from the notches Q', in the angle-irons Q, which permits of pulling the several pieces apart.

The lounge is provided with the usual casters, and can be upholstered in any suitable manner. In case that two angle-irons are 70 used for each corner, the upper angle-iron rests on the top edge of the lower plate, M, as shown in Figs. 1 and 3.

Having thus fully described my invention, I claim as new and desire to secure by Letters 75 Patent—

1. The combination, with the lounge A, of a box or trunk, B, consisting of the removable side pieces, C, D, E, and F, the bottom G, supported on the plates I, and the hinged seat 80 H, substantially as shown and described.

2. In a lounge, the combination of the rear part, C, the front part, F, the head part D, the foot cross-piece E, the bottom G, and the hinged seat H, with the plates M, having the 85 guide-strips N, the pawls O, the bottom guide-plate, P, and the angle-irons Q, having the notches Q', substantially as shown and described.

3. In a lounge, the combination of two side 90 pieces, the plates M, having guide-strips N, attached to the said side pieces, the pawls O, and the bottom plate, P, with the angle-irons Q, having notches Q', substantially as shown and described.

HENRY BURGESS.
